Attorney

UNITED STATES PATENT OFFICE.

JACOB B. OTTENHEIMER, OF BALTIMORE, MARYLAND, ASSIGNOR TO OTTENHEIMER BROTHERS, INCORPORATED, OF BALTIMORE, MARYLAND, A CORPORATION OF MARYLAND.

REFRIGERATOR.

Application filed March 5, 1924. Serial No. 697,060.

To all whom it may concern:

Be it known that I, JACOB B. OTTENHEIMER, a citizen of the United States, residing at Baltimore city, State of Maryland, have invented certain new and useful Improvements in Refrigerators, of which the following is a specification.

This invention relates to refrigerators, one of its objects being to provide separate and distinct ice and food compartments having a novel arrangement of openings whereby the distribution of air flowing through the compartments is rendered more efficient than heretofore, resulting in elimination of air pockets in the food chamber, distribution of the air suction or "pull" to all parts of said chamber, and more effective flow of air over the ice.

A further object is to provide means for controlling the flow of air through the chambers.

With the foregoing and other objects in view which will appear as the description proceeds, the invention consists of certain novel details of construction and combinations of parts which will be hereinafter more fully described and pointed out in the claims, it being understood that various changes may be made in the construction and arrangement without departing from the spirit of the invention.

In the accompanying drawings the preferred forms of the invention have been shown.

35 In said drawings—

Figure 1 is a vertical transverse section through the refrigerator.

Figure 2 is a section on line 2—2, Figure 1.

40 Figure 3 is a section on line 3—3, Figure 1.

Figure 4 is a section through a portion of a refrigerator having a controlling shutter.

45 Referring to the figures by characters of reference, 1 designates the housing or casing of the refrigerator having insulated walls, top and bottom, as shown. The bottom 2 of the ice compartment 3 is located above the bottom of the housing and one 50 side of the lower end of a partition 4 which divides the interior of the refrigerator into the ice compartment 3 and a food compartment 5. An air outlet is located at the top of the food compartment, as shown at 5'. 55 This opens through the top wall of the food

compartment and is spaced away from the partition wall 4. For best effect it is located at the center of the top of the food compartment and extends from front to rear thereof. This outlet opens into a flue 6 extending laterally and opening into the top of the ice chamber directly above the partition 4. Another air outlet 7 is formed in the bottom 2 and extends from the front to back thereof at the center. The usual ice supporting tray bridges this opening, as at 8 and is so supported as not to interfere with the circulation of air. The walls, top and bottom of the casing 1 are suitably insulated as is also the partition 4.

70 It will be apparent that when ice is placed in compartment 3 the chilled air will flow downwardly through outlet 7 and displace the warm air which rises within compartment 5. This warm air flows through the outlet 5' and flue 6 to the top of the ice compartment 3 where it is chilled and flows downwardly to the outlet 7. The circulation thus set up creates a decided "pull" upon the air in all portions of the compartment 5 so that there are no dead air pockets such as usually found in the corners and along one or more of the walls of the provision compartments such as usually constructed. This result follows from the careful location of the openings 5' and 7 and in some degree from the fact that these extend from front to back of the refrigerator. The location of the outlet 5' in the top wall of the food compartment minimizes the danger 80 of choking of the outlet by foodstuffs on the top shelf S, and the relative arrangements of the compartments allows for greater shortage of ice than would be possible with other arrangements where the same 85 food storage space is used.

90 The construction shown in Fig. 4 is essentially identical with that shown in the remaining figures, except that the opening 5' is larger than that shown in the remaining figures, and is controlled by adjustable louvers or shutters 9, by which the rate of air circulation may be controlled if desired.

95 What is claimed is:—

100 1. A refrigerator comprising in combination a heat insulated casing; a partition extending vertically within the casing from a point below its top to a point above its bottom, said partition serving to isolate a cool- 105

- ing medium receiving space from a food receiving space, both within said casing, except as to convection air currents circulating between said spaces over its top and beneath its bottom; means within said casing serving to define a smooth flow duct for relatively warm air leading through the top wall of said food receiving space at a point spaced from said partition and thence over the top of said partition and into said cooling medium receiving space; and means for supporting a cooling medium above the lower margin of said vertical partition.
- 5 2. A refrigerator comprising in combination a heat insulated casing; a heat insulated partition extending vertically within the casing from a point below its top to a point above its bottom, said partition serving to isolate a cooling medium receiving space from a food receiving space, both within said casing, except as to convection air currents circulating between said spaces over its top and beneath its bottom; means within said casing serving to define a smooth flow duct for relatively warm air leading through the top wall of said food receiving space at a point spaced from said partition and thence over said partition and into said cooling medium receiving space, 10 said duct extending substantially the full depth of said space from front to back of the refrigerator; adjustable means for regulating the flow through said duct; and means for supporting a cooling medium above the lower margin of said vertical partition.
- 15 3. A refrigerator comprising in combination a heat insulated casing; a heat insulated partition extending vertically within the casing from a point below its top to a point above its bottom, said partition serving to isolate a cooling medium receiving space from a food receiving space, both within said casing, except as to convection air currents circulating between said spaces over its top and beneath its bottom; means within said casing serving to define a smooth flow duct for relatively warm air leading through the top wall of said food receiving space at a point spaced from said partition and thence over said partition and into said cooling medium receiving space, 20 said duct extending substantially the full depth of said space from front to back of the refrigerator; adjustable means for regulating the flow through said duct; and means for supporting a cooling medium above the lower margin of said vertical partition.
- 25
- 30

spaces from front to back of the refrigerator; and means for supporting a cooling medium above the lower margin of the vertical partition.

35 3. A refrigerator comprising in combination a heat insulated casing; a heat insulated partition extending vertically within the casing from a point below its top to a point above its bottom, said partition serving to isolate a cooling medium receiving space from a food receiving space, both within said casing, except as to convection air currents circulating between said spaces over its top and beneath its bottom; means within said casing serving to define a smooth flow duct for relatively warm air leading through the top wall of said food receiving space at a point spaced from said partition and thence over said partition and into said cooling medium receiving space, 40 said duct extending substantially the full depth of said space from front to back of the refrigerator; adjustable means for regulating the flow through said duct; and means for supporting a cooling medium above the lower margin of said vertical partition.
